Primary Examiner — T. Chase Nelson(74) *Attorney, Agent, or Firm* — Thompson Coburn LLP(57) **CLAIM**

The ornamental design for a shoe sole, as shown and described.

DESCRIPTION

FIG. 1 is a perspective view of a shoe sole showing the new design;

FIG. 2 is a bottom plan view thereof;

FIG. 3 is a medial side view thereof;

FIG. 4 is a lateral side view thereof;

FIG. 5 is a front view thereof; and,

FIG. 6 is a rear view thereof.

The broken lines immediately adjacent the shaded area represent unclaimed boundaries of the design. The broken lines showing the remainder of the shoe and the tread pattern are for the purpose of illustrating environmental structure and form no part of the claimed design.
